COMBINED PLAYING CARD RACK AND HOLDER

Harry Koppelman, New York, N. Y.

Application August 10, 1948, Serial No. 148,018

Term of patent 3½ years

(Cl. D34—13)

To all whom it may concern:

Be it known that I, Harry Koppelman, a citizen of the United States, residing at New York city, in the county of the Bronx and State of New York, have invented a new, original and ornamental Design for a Combined Playing Card Rack and Holder, of which the following is a specification, reference being had to the accompanying drawing, forming part thereof.

Fig. 1 is a perspective view of a combined playing card rack and holder, showing my new design.

Fig. 2 is a side view thereof.

Fig. 3 is a top plan view thereof.

Fig. 4 is an end view thereof.

Fig. 5 is a side view thereof, showing the device as it appears when in use as a holder.

Fig. 6 is a similar view showing the device as it appears when in use as a card rack.

The dotted line illustrations in Figs. 5 and 6 are for illustrative purposes only.

I claim:

The ornamental design for a combined playing card rack and holder, substantially as shown and described.

HARRY KOPPELMAN.
